Specification for Design.

Patented Feb. 4, 1913.

Application filed June 10, 1912. Serial No. 702,893. Term of patent 7 years.

To all whom it may concern:

Be it known that I, MELVILLE G. CURTIS, a citizen of the United States, residing at Bala, in the county of Montgomery and State of Pennsylvania, have invented a new, original, and ornamental Design for Textile Fabric, of which the following is a specification, reference being had to the accompanying drawing, forming part thereof.

The figure illustrates a section of fabric embodying my design which comprises parallel stripes of different shades, each stripe

consisting of a solid body portion having laterally extending projections which lap and alternate with laterally extending projections of adjacent stripes.

I claim:

The ornamental design for a textile fabric as shown and described.
